(57) **CLAIM**

The ornamental design for a backpack with hat and boot compartments, as shown and described.

DESCRIPTION

FIG. 1 is a perspective view of a backpack with hat and boot compartments.

FIG. 2 is a front view of the backpack with hat and boot compartments of FIG. 1.

FIG. 3 is a back view of the backpack with hat and boot compartments of FIG. 1.

FIG. 4 is a left side view of the backpack with hat and boot compartments of FIG. 1.

FIG. 5 is a right side view of the backpack with hat and boot compartments of FIG. 1.

FIG. 6 is a top view of the backpack with hat and boot compartments of FIG. 1.

FIG. 7 is a bottom view of the backpack with hat and boot compartments of FIG. 1.

FIG. 8 is a perspective view of another embodiment of a backpack with hat and boot compartments.

FIG. 9 is a front view of the backpack with hat and boot compartments of FIG. 8.

FIG. 10 is a back view of the backpack with hat and boot compartments of FIG. 8.

FIG. 11 is a left side view of the backpack with hat and boot compartments of FIG. 8.

FIG. 12 is a right side view of the backpack with hat and boot compartments of FIG. 8.

FIG. 13 is a top view of the backpack with hat and boot compartments of FIG. 8; and,

FIG. 14 is a bottom view of the backpack with hat and boot compartments of FIG. 8.

The broken lines of the drawings are for the purpose of illustrating portions of a backpack with hat and boot compartments that form no part of the claim.

1 Claim, 14 Drawing Sheets
